UNITED STATES PATENT OFFICE

172,077

TEAPOT OR SIMILAR ARTICLE

A. Baker Barnhart, New York, N. Y., assignor to
The Rosenthal-Block China Corporation, New York, N. Y.

Application April 14, 1953, Serial No. 24,495

Term of patent 14 years

(Cl. D44—26)

To all whom it may concern:

Be it known that I, A. Baker Barnhart, a citizen of the United States, residing in the city of New York, State of New York, have invented a new, original, and ornamental Design for a Teapot or Similar Article, of which the following is a specification, reference being had to the accompanying drawing, forming a part hereof.

Figure 1 is a side elevational view of a teapot or similar article showing my new design;

I claim:

The ornamental design for a teapot or similar article, as shown.
